UNITED STATES PATENT OFFICE.

BURT D. STEVENS, OF RIVERSIDE, ILLINOIS, ASSIGNOR TO THE MIEHLE PRINTING PRESS & MANUFACTURING COMPANY, OF CHICAGO, ILLINOIS, A CORPORATION OF ILLINOIS.

PRINTING-PRESS.

1,145,936.

Specification of Letters Patent. Patented July 13, 1915.

Application filed September 11, 1911. Serial No. 648,684.

To all whom it may concern:

Be it known that I, BURT D. STEVENS, a citizen of the United States, residing at Riverside, in the county of Cook and State 5 of Illinois, have invented certain new and useful Improvements in Printing-Presses, of which the following is a specification.

My invention relates to printing presses, and refers particularly to the mechanism by 10 which the proper pressure is obtained between the impression cylinder and the printing form sheet carried by the press-bed or carriage which reciprocates beneath the impression cylinder.

15 In lithographic printing it is of particular advantage to use sheets of metal instead of lithographic stones on account of the much less cost of the former. In order to prevent the tendency for the sheet of metal 20 to bulge when it is applied to the press-bed, it is of advantage to make the upper surface of said press-bed with a slight convex curve, thereby causing the metal sheet to fit snugly on such upper surface. It has heretofore 25 been customary, as disclosed, for example, in Patent No. 932,100, granted to B. F. Berry, to operate the press-bed on a curved track having the same curvature as that of the upper surface of the press-bed so that a 30 uniform pressure will be exerted by the impression cylinder on the surface of the press-bed as the latter reciprocates back and forth.

It is the object of my invention to do away with the necessity of using a curved 35 track, which is very difficult to construct. I employ a straight track on which the press-bed moves, and in order to cause the impression cylinder to maintain a substantially uniform pressure on the press-bed I mount 40 said cylinder in spring-controlled bearings which are movable in a vertical plane. It is of advantage to elevate the impression cylinder on the return stroke of the press-bed, and in order to accomplish this I employ a 45 cam, or other suitable device, to automatically accomplish the desired result.

A further object of my invention consists 50 in providing resilient means for exerting pressure between the impression cylinder and the press-bed, irrespective of the shape of the latter and irrespective of whether a straight or a curved track is used. This is a considerable departure and improvement in the art, as heretofore it has been considered 55 necessary to retain the impression cylinder

in fixed position while it is in contact with the press-bed, although I am aware that spring means have, in some cases, been employed to move the impression cylinder into its inoperative position on the return movement of the press-bed.

These and other advantages of my invention will be more readily understood by reference to the accompanying drawings, which show a preferred embodiment of my improvements, and in which—

Figure 1 is a side elevation of a portion of a printing press showing the press-bed, the impression cylinder, and the mechanism controlling the same; and Fig. 2 is a fragmentary sectional view taken on the line 2—2 of Fig. 1.

The main frame 5 of the printing press is provided with the supporting brackets 6 having the cross-members 7. The bearings 75 8 are adapted to reciprocate within the slots 9 of the brackets 6, and these bearings are, in turn, supported by the rods 10, which extend downwardly to the cross-members 11, which are provided with the downward projections 12, the object of which will be explained hereafter. Extending between the upper surfaces of the bearings 8 and the brackets 6 are the compression springs 13, which are held in position by the upper 85 ends of the rods 10 and the disks 14, the position of which are regulated by the screws 15 so that the tension on the springs 13 may be varied as desired.

The impression cylinder 16 having the 90 shaft 17 is carried by the bearings 8. The press-bed 18 operates on the rollers 19, which, in turn, move on the straight tracks 20. The upper surface of the press-bed is slightly convex, and to it is applied the 95 printing sheet 20, preferably of zinc, and suitably attached at its ends to the press-bed 18.

The lower ends of the extensions 12 of the cross-members 11 are provided with concave 100 surfaces which engage the cams 21. These cams are operated by a lever 22, which is, in turn, suitably controlled by the link 23.

Having thus described the construction of the parts used in my invention, the operation 105 of the same may now be readily understood: The impression cylinder rotates in a clockwise direction, as indicated by the arrow, and while the press-bed is withdrawn from engagement with the impression cyl- 110

inder and occupies a position to the right of the latter, according to the representation shown in Fig. 1, the lever 22 is in its elevated position, and, on account of the shape 5 of the cam 21, the bearings 8 are thereby allowed to come into their lowermost positions. The press-bed 18 is now moved to the left in a straight path, and the left-hand end of the sheet 20 comes in contact 10 with the periphery of the impression cylinder 16. As the press-bed continues to be moved to the left the upper convex surface of the press-bed 18, or the similarly shaped bearers on the sides thereof, which engage 15 the edges of the impression cylinder, causes the latter to be forced upwardly against the tension of the springs 13. On account of the very slight degree of curvature of the upper surface of the press-bed 18, the compression 20 of the springs 13 is very slight, and an even tension is thereby obtained on the printing sheet 20, or, rather, on the sheet of paper which is applied to the latter for the purpose 25 of being printed.

After the press-bed 18 is moved to the left a sufficient distance so that it is freed from the impression cylinder 16, the link 23 is moved downwardly by suitable mechanism (which, for the sake of simplicity, is not 30 here shown), whereby the cam 21 elevates the extension 12, and, thereby, the bearings 8 and the impression cylinder 16. When the press-bed 18 is moved to the right on its return stroke, it is therefore entirely clear 35 of the impression cylinder 16.

It will be readily understood by those

skilled in the art that many changes could be made in the detailed construction of the parts which I have described without departing from the spirit or scope of my invention. 40

What I claim is:

1. A printing couple comprising in combination a non-rotary member having a slightly curved printing surface and arranged to reciprocate in a straight path, a second member adapted to coact with the printing surface on the first member, and means to yieldingly press the two members together 45 in printing relation. 50

2. A printing couple comprising in combination a non-rotary bed having a slightly convexed printing surface, and arranged to reciprocate in a straight path, an impression cylinder adapted to coact with the printing surface of the bed, and means to yieldingly press the cylinder against the bed 55 in printing relation.

3. A printing couple comprising in combination a non-rotary bed having a slightly 60 convexed printing surface and arranged to reciprocate in a straight path, a rotary impression cylinder mounted in stationary bearings for slight movement toward and from the bed and adapted to co-act with the 35 printing surface thereof, and means to yieldingly press the cylinder toward the bed.

BURT D. STEVENS.
